[57] CLAIM

The ornamental design for a remote control holder, as shown and described.

DESCRIPTION

FIG. 1 is a top, front and left side perspective view of a remote control holder showing my new design.

FIG. 2 is a bottom plan view thereof;

FIG. 3 is a right side elevational view thereof;

FIG. 4 is a left side elevational view thereof;

FIG. 5 is a plan view of the embodiment of FIG. 3.

The rear of the remote control holder is plane and unornamented.
